DERIVATIVE OF TROPIC ACID AMIDE

Wilhelm Wenner, Montclair, N. J., assignor to
Hoffmann-La Roche Inc., Nutley, N. J., a corporation of New Jersey

No Drawing. Original application June 26, 1939,
Serial No. 281,269. Divided and this application
October 14, 1942, Serial No. 462,063. In
Germany July 7, 1938

4 Claims. (Cl. 260—559)

The need for an effective choleretic has become more and more evident in recent years since it has been established that by increasing the secretion of bile, illnesses of the liver and bile ducts can be favorably influenced. A number of 5 chologenic preparations have in fact already been placed on the market. The better known among them contain as active substances bile acid derivatives, podophyllin, as well as extracts from plants (e. g. radish extract). Extracts from liver and gall bladder have also been employed as choleric.

It has now been found that tropic acid amide and its neutral N-substituted derivatives possess a strong cholagogic action.

Only tropic acid amide has been described in the literature up to the present (Annalen der Chemie, vol. 389, year 1912, page 111). This was obtained through the following intermediate stages: Tropic acid, atropic acid, β -bromo- α -phenyl propionic acid. The manufacture of atropic acid as well as of β -bromo- α -phenyl-propionic acid does not proceed satisfactorily because the formation of by-products cannot be avoided (Annalen der Chemie, vol. 209, year 1881, page 12, 20 paragraph 4). Likewise, the transformation of β -bromo- α -phenyl propionic acid into tropic acid amide can only be carried out in poor yield, since atropic acid as well as atrolactic acid and styrol occur as by-products (Annalen der Chemie, vol. 30 115, year 1860, page 159; vol. 209, year 1881, page 11). This process cannot therefore be taken into consideration for the technical synthesis of tropic acid amide.

The disadvantages described can be avoided if 35 tropic acid amide is obtained by allowing ammonia to act on o-acetyl tropic acid chloride. The ammonia may be employed in aqueous solution or in a suitable organic solvent, such as benzene, toluene, ether, chloroform, petroleum ether. o-Acetyl tropic acid amide is obtained in very good yield. By treating this compound with acids or alkalis under suitable conditions, the acetyl group is split off.

If amines, e. g., aliphatic primary and secondary 45 amines, cycloalkyl amines, are caused to act on o-acetyl tropic acid chloride in the same manner, the corresponding substituted amides of o-acetyl tropic acid are obtained. The amines employed are also best used in solution in water or in an 50 organic solvent. The acetyl group is split off by treatment with alkalis or acids from the resulting o-acetyl tropic acid amides substituted in the amido group.

Tropic acid amide and its neutral N-substituted 55

derivatives are colorless compounds. The lower members of the series are crystalline, the higher members mostly liquids. They are to be employed as choleric. The examination of the cholagogic action was carried out in accordance with Grabe's process (Archiv für experimentelle Pathologie und Pharmakologie, vol. 176, year 1934, page 673). According to this method the gall secretion in the narcotised rat is first determined over a period of 2 hours, the preparation to be examined then administered by means of a stomach tube, and the ensuing change in the gall secretion observed.

The comparison of tropic acid dimethyl amide with desoxycholic acid, whose choleric action is 15 described in the literature (Biochemische Zeitschrift, vol. 130, year 1922, page 556; Zeitschrift für die gesamte experimentelle Medizin, vol. 30, year 1922, page 423), clearly shows the superiority of the new class of compounds.

	20	25	19	14	-26

Example 1

45 parts by weight of o-acetyl tropic acid chloride are added dropwise to 56 parts by weight of aqueous ethylamine solution (33 per cent) while stirring, the temperature being kept at 20-30° C. The reaction mixture is extracted with benzene. After evaporation of the benzene, about 35 parts by weight of crude o-acetyl tropic acid ethylamide are obtained. By short heating with a dilute solution of caustic soda the acetyl group is split off and tropic acid ethylamide of melting

point 129° C. is obtained. The yield is about 80 per cent of the theoretical.

If allylamine is used instead of ethylamine, the above reaction produces tropic acid allyl amide melting at 140° C.

Example 2

45 parts by weight of o-acetyl tropic acid chloride are added drop by drop to 55 parts by weight of aqueous dimethylamine solution (32 per cent) while stirring and cooling with ice. By extraction with benzene, 44 parts by weight of o-acetyl tropic acid dimethyl amide of melting point 68° C. are obtained. By heating with a 12 per cent solution of caustic soda, the acetyl group is removed and 30 parts by weight of tropic acid dimethyl amide melting at 96° C. are obtained.

Example 3

45 parts by weight of o-acetyl tropic acid chloride are dissolved in 100 parts by weight of chloroform and added dropwise to 30 parts by weight of diethylamine in 100 parts by weight of chloroform while stirring and cooling. The solution is evaporated to dryness and the residue treated with water and benzene. The benzene solution is separated and evaporated to dryness. The residue is left to stand with a mixture of 200 parts by weight of methanol and 40 parts by weight of concentrated hydrochloric acid at room temperature for 2 days. The mixture is then neutralized and evaporated to dryness. Tropic acid diethylamide of melting point 84° C. is obtained.

Example 4

45 parts by weight of o-acetyl tropic acid chloride are dissolved in 120 parts by weight of benzene and added dropwise to a solution of 52 parts by weight of di-n-butylamine in 350 parts by weight of benzene while stirring and cooling. The reaction mixture is extracted with water and the benzene solution evaporated. The acetyl group is split off by the action of aqueous alcoholic alkali. Tropic acid di-n-butylamide is obtained which melts at 61° C.

This application is a division of my application Serial No. 281,269, filed June 26, 1939.

What I claim is:

15 1. A derivative of tropic acid amide of the formula

20 25 wherein R' is selected from the group consisting of hydrogen and a lower alkyl and R'' is a lower alkyl.

2. Tropic acid mono-ethylamide.
3. Tropic acid dimethylamide.
4. Tropic acid diethylamide.

30 WILHELM WENNER.
